INVENTOR,
Henry Braen.
BY
John, Edward,
ATTORNEY.

UNITED STATES PATENT OFFICE.

HENRY BRAEN, OF PATERSON, NEW JERSEY, ASSIGNOR TO THE INVENTORS NOVELTY MANUFACTURING COMPANY, OF NUTLEY, NEW JERSEY, A CORPORATION OF NEW JERSEY.

SAMPLE-CASE.

1,264,150.

Specification of Letters Patent. Patented Apr. 30, 1918.

Application filed June 9, 1916. Serial No. 102,658.

To all whom it may concern:

Be it known that I, HENRY BRAEN, a citizen of the United States, residing at Paterson, in the county of Passaic and State of New Jersey, have invented certain new and useful Improvements in Sample-Cases, of which the following is a specification.

The invention relates to cases used especially for the display of samples and embodying one or more stacks of trays or like receptacles hinged together by means of links in lazy-tong fashion so that each stack of trays, in closed position standing superimposed squarely upon each other, may be 15 extended into stepped disposition to display their contents. My object is to simplify the construction of such cases and to strengthen each jointed series of trays when in the open or extended position.

20 In the accompanying drawing,

Figure 1 is an end elevation of the improved case, showing one stack of the trays in closed and the other in extended position; and,

25 Fig. 2 is a fragmentary plan of what appears in Fig. 1.

a is the bottom or base tray or receptacle, which may or may not be detachable from the base *b*, which has hinged to it the cover 30 sections *c c*.

35 *d d* denotes the removable trays or receptacles, here shown in two series arranged upon the base tray *a*. The trays are all rectangular in plan, each tray *d* being in the present case one-half of the area of tray *a*.

The several trays *d* in each series are connected at their ends with each other and with the ends of tray *a* by the links *e*, the 40 novel construction of which constitutes the essential feature of this invention. That is to say:

45 Each link *e* is a flat bar preferably straight in its body portion but having a lateral projection *f* at each end, the two projections being at opposite edges *f* of the bar. The projections *f* extend beyond the ends *h* of the body portion of each bar somewhat to form shoulders *g*, and said ends of the body portion of the bar are oblique to its longitudinal 50 axis but parallel to each other, the obliquity being such that each edge *h* forms an acute angle with that side or edge *f* of the body part of the bar from which the corresponding projection *f* extends. This description 55 applies to all the links excepting the end

links, whose inner ends are formed as already described while their outer ends are left plain, as shown, said links being also shorter than the others.

The links are connected with the ends of 60 the trays by pivoting rivets *i* or equivalent means in such manner that they will be parallel, but inclined with respect to the trays, when the trays are nested or in closed position but will form a substantially straight 65 line when the trays are extended. That is to say, there are three equidistant pivots *i* in a horizontal central line for each end of each of the trays except the tray *a* and uppermost tray *d*, which respectively have at each end 70 but two pivots *i*. The links (except the end links) are each connected with three adjoining trays so that the middle pivot of the middle tray is at the middle of such link and one right and one left pivot of the other two 75 trays is at the projections *f* of the link; the end links have those pivots *i* of the two trays at each end of the series not utilized in the manner just explained arranged at their outer ends and projections *f* in a manner 80 conforming to the arrangement of the other pivots with respect to the corresponding points of the other links.

The arrangement is further such that when the trays are moved to the open position, the links will abut each other and so serve mainly to support the trays, which need not even touch each other, though they are shown in the drawing as touching. Preferably, as explained, the end portions of the 85 links in effect form notches or locking or detent shoulders *g-h*, which positively and without slipping or wiping stop the opening movement of the trays as soon as such shoulders abut each other. This construction 90 gives solidity and rigidity to the extended trays and distributes the strains to the best advantage and further imposes the strains more on the links than on the trays, which are usually made of wood and therefore according to the constructions usually employed have to be reinforced to protect them against splitting or other injury incident to the weight of their contents and to frequent 95 opening and closing movements.

Having thus fully described my invention, what I claim as new and desire to secure by Letters Patent is:

1. The combination of a series of receptacles and parallel links connecting the re- 110

ceptacles lazy-tong fashion, the thus-connected series of receptacles and links being movable to a position wherein the receptacles assume stepped disposition and the 5 links in each series have each intermediate link therein in contact at both ends thereof with the two adjoining links.

2. The combination of a series of superposed receptacles and parallel links connecting the receptacles lazy-tong fashion, each 10

two adjoining links having at their adjoining ends lateral projections projecting in relatively opposite directions and affording the pivots between such links and the two corresponding receptacles and being adapted 15 to abut each other and limit the lazy-tong movement of said series of receptacles and links.

In testimony whereof I affix my signature.
HENRY BRAEN.
